Primary Examiner — Darlington Ly

(57) **CLAIM**

The ornamental design for a T-handle for a valve, as shown and described.

DESCRIPTION**1. T-handle for a valve**

1.1 is a right side elevation view of the T-handle for a valve showing my new design;

1.2 is a left side elevation view thereof;

1.3 is a top plan view thereof;

1.4 is a bottom plan view thereof;

1.5 is a front elevation view thereof;

1.6 is a rear elevation view thereof;

1.7 is a front, top, and right side perspective view thereof;

1.8 is a front, top, and left side perspective view thereof;

1.9 is a rear, top, and right side perspective view thereof; and

1.10 is a rear, top, and left side perspective view thereof.

1 Claim, 10 Drawing Sheets
